UNITED STATES PATENT OFFICE

ALBERT W. ECKBLOM, OF ST. PAUL, MINNESOTA

DESIGN FOR AN ADVERTISING SIGN

Application filed November 7, 1932. Serial No. 45,806. Term of patent 3½ years.

To all whom it may concern:

Be it known that I, ALBERT W. ECKBLOM, a citizen of the United States, residing at St. Paul, in the county of Ramsey and State of Minnesota, have invented a new, original, and ornamental Design for an Advertising Sign, of which the following is a specification, reference being had to the accompanying drawing, forming part thereof.

Fig. 1 is a face view and Fig. 2 is an edge view of an advertising sign, showing my new design.

The cross patching on the drawing indicates contrasting colors.

I claim:

The ornamental design for an advertising sign, as shown and described.

ALBERT W. ECKBLOM.
